CONTAINER CAP

George W. Ittner, St. Louis, Mo., assignor of
one-half to John B. Hulett, New York, N. Y.

Application February 5, 1932. Serial No. 591,003

5 Claims. (Cl. 221—60)

My invention relates particularly to that type of removable caps which are secured to the screw-threaded nozzles or necks of containers or compressible tubes for viscous substances, such as 5 tooth paste, shaving creams, and the like.

The objects of my invention are, among other things, to provide an improved and simplified means for attaching the cap to the receptacle or container with ready means for removal and 10 also for fastening same to the container so as to lock and seal completely the contents. My improved attachment not only holds the cap clear from the nozzle when the container contents are to be expressed from the tube in use, 15 but also readily permits the cap to be replaced in closed and sealing position and then securely held on the nozzle.

With these and other objects in view, my invention comprises the novel construction and 20 arrangement of parts hereinafter described and thereafter particularly pointed out in the claims.

A preferred embodiment of my container cap attachment is shown in the accompanying drawing in which—

25 Fig. 1 is a side elevation partly in section showing the cap in closed or locked position;

Fig. 2 is a top plan view showing the cap in open position;

Fig. 3 is a side elevation looking from the right 30 in Fig. 1;

Fig. 4 is an enlarged side elevation of a modified form in closed position;

Fig. 5 is a side elevation looking from the right in Fig. 4 but with the collar unscrewed; and

35 Fig. 6 is an enlarged detail view on the line 6—6 of Fig. 4.

Similar numerals refer to similar parts throughout the several figures.

Referring to the drawing, the container or tube 40 receptacle 7 has the shoulder 8 at its upper or open end terminating in the exteriorly screw-threaded nozzle 9 provided with the opening 10 through which the contents of the tube 7 pass when the latter is compressed. Mounted on the 45 screw-threaded nozzle 9 is the interiorly screw-threaded collar 11 which carries the spaced-apart brackets 12 holding the pin 13 upon which the spaced-apart lugs 14 of the circular cap 15 are pivoted as shown in Figs. 1 and 2. Preferably the spring 16 is coiled about the pin 13 between the lugs 14 with its upper end 17 bearing against the concave crown 18 of the cap 15 to normally hold the latter in its open Fig. 2 55 position, but such spring 16 may be dispensed with.

The cap 15 has the depending skirt 19 from which projects the depending hook 20 which is adapted to engage the lug 21 formed exteriorly on the collar 11 opposite the brackets 12. The collar 11 also carries the inclined arm 22 which 60 is adapted to bear on the shoulder 8 when the collar is screwed home, but the arm 22 engages the stop lug 23 on the shoulder 8 when the collar 11 is reversely unscrewed whereby the movements of the collar 11 are limited in both directions. 65

Referring to the modified form shown in Figs. 4—6, the collar 11 is provided with the single bracket 24 with the bore 25 through which passes the U-shaped wire 26 secured to the cap 15 to form a hinged joint for the cap 15. As shown in Fig. 6, the shape of the wire 26 allows for loose play for the cap 15 and this form may dispense with the spring 16 used in the Figs. 1—3 construction. As shown in Fig. 5 the collar 11 is additionally provided with the guide 27 to allow the 70 hook 20 to pass between the lug 21 and guide 27; such hook may be shifted laterally so as to be disengaged from the lug 21 upon raising of the cap 15 as shown in dotted lines in Fig. 5. The other parts shown in Figs. 4—6 are the same as corresponding parts in Figs. 1—3 already described. 75

In operation, when the cap 15 is in its Fig. 2 open position, the container is sealed by the operator pressing the cap 15 down to its Fig. 3 position against the tension of the spring 16 by which 80 the hook 20 snaps by the lug 21 and engages therewith as shown by dotted lines in Fig. 3. Then the cap 15 with collar 11 is screwed down on the nozzle 9 by twisting in a clockwise direction (Fig. 2), until the arm 22 presses firmly on the shoulder 8 which frictional engagement locks the collar 11 and cap 15 in place with the concave crown 18 sealing the nozzle opening 10 as shown in Figs. 2 and 3. The nozzle 9 is opened by twisting the cap 15 and collar 11 from their Fig. 1 to 85 their Fig. 2 position until the arm 22 engages stop lug 23; a slight continued movement of the cap 15 will disengage the hook 20 from the lug 21 and then the cap 15 will be raised by the spring 16 to its Fig. 2 position, or the cap 15 may be lifted 95 manually if no spring 16 is used as shown in the Figs. 4—6 construction. 100

In this Figs. 4—6 modification the loose play at the hinge of the cap 15 allows the hook 20 readily to pass between the lug 21 and guide 27 as shown in Fig. 5 with the arm 22 limiting the rotary movement of the collar 11 on the nozzle 9 in the same manner as in the Figs. 1—3 construction. 105

It will be understood that this removable container cap attachment herein shown and de- 110

scribed may be variously modified in details without departing from the scope of my invention or sacrificing the advantages derived from its use.

I claim as my invention:—

- 5 1. A container having an exteriorly screw-threaded nozzle, an interiorly threaded collar on said nozzle, a cap hinged to said collar, coacting means on the cap and collar oppositely disposed from the cap hinge to hold the cap on the nozzle, and means arranged on said collar and container 10 permitting only a limited rotary movement of the collar on said nozzle in both directions when removing and securing the cap.
- 15 2. A container having an exteriorly screw-threaded nozzle, an interiorly threaded collar on said nozzle, a cap hinged to said collar and having a spring normally holding the cap away from the nozzle, coacting means on the cap and collar oppositely disposed from the cap hinge to hold the cap on the nozzle while compressing said spring, and means arranged on said collar and container 20 permitting only a limited rotary movement of the collar on said nozzle in both directions when removing and securing the cap.
- 25 3. A container having an exteriorly screw-threaded nozzle centrally disposed on the container shoulder, an interiorly threaded collar on said nozzle, a cap hinged to said collar, a depending hook member on said cap, a lug on said collar 30 to engage with said hook member when the cap is seated on the nozzle and collar, said hook member and lug being disposed opposite to said cap hinge, and means carried by the collar to frictionally

engage on the container shoulder to limit the rotary movement of both cap and collar when the latter is screwed down on said nozzle.

4. A container having an exteriorly screw-threaded nozzle centrally disposed on the container shoulder, an interiorly threaded collar on said nozzle, a cap hinged to said collar and having a spring normally holding the cap away from the nozzle, a depending hook member on said cap, a lug on said collar to engage with said hook member when the cap is seated on the nozzle and collar while compressing said spring, said hook member and lug being disposed opposite to said cap hinge, and means carried by the collar to frictionally engage on the container shoulder to limit the rotary movement of both cap and collar when the latter is screwed down on said nozzle.

5. A container having an exteriorly screw-threaded nozzle centrally disposed on the container shoulder, an interiorly threaded collar on said nozzle, a cap hinged to said collar, a depending hook member on said cap, a lug on said collar to engage with said hook member when the cap is seated on the nozzle and collar, said hook member and lug being disposed opposite to said cap hinge, means carried by the collar to frictionally engage on the container shoulder to limit the rotary movement of both cap and collar when the latter is screwed down on said nozzle, and means to limit the rotary movement of the collar when unscrewed from the nozzle to release the cap.

GEORGE W. ITTNER.
